Primary Examiner — Cynthia R Underwood(74) *Attorney, Agent, or Firm* — Alleman Hall Creasman & Tuttle LLP(57) **CLAIM**

The ornamental design for a cable clip, as shown and described.

DESCRIPTION

FIG. 1 is a perspective view of an ornamental design for a cable clip.

FIG. 2 is another perspective view of the cable clip of FIG. 1.

FIG. 3 is a front elevation view of the cable clip of FIG. 1.

FIG. 4 is a back elevation view of the cable clip of FIG. 1.

FIG. 5 is a left elevation view of the cable clip of FIG. 1.

FIG. 6 is a right elevation view of the cable clip of FIG. 1.

FIG. 7 is a top plan view of the cable clip of FIG. 1; and,

FIG. 8 is a bottom plan view of the cable clip of FIG. 1.

FIGS. 1-8 depict an ornamental design for a cable clip including a central region and two arms. The cable clip may be used to secure a cable, for example to a surface via use of a fastener.
